RALPH J. KERRUISH, OF LITTLETON, COLORADO

CURB BIT

Application filed February 1, 1930. Serial No. 425,246.

The present invention relates to bridle bits and more particularly to a bridle bit which is adapted to be used as a curb bit for horses and which is so constructed as to permit its ready use for a horse which is docile or not inclined to be unruly.

An object of this invention is to provide a bit which is so constructed as to readily curb an unruly horse without inflicting undue punishment on the horse or injuring the mouth of the horse.

Another object of this invention is to provide a humane curb bit particularly adapted for horses being used in sports of various kinds wherein an unusual amount of turning, stopping, or checking is done, and is also designed for use in ordinary riding of horses.

A further object of this invention is to provide a bit of this character which is adapted for use in gaiting horses or the like and for horses which have tender mouths, the bit being so constructed as not to injure a tender mouth and at the same time provide ample curbing capacities so that the horse will at all times be under complete control of the rider.

A still further object of this invention is to provide a bit which, while suitable for use with horses having tender mouths, is also suitable for use with horses having what is commonly termed a tough mouth. The tough mouth is sometimes caused by the mouth corners being pinched, pinching generally causing lunging, rearing and head fighting.

The above and various other objects and advantages of this invention will in part be described in and in part be understood from the following detailed description of the present preferred embodiment, the same being illustrated in the accompanying drawing wherein:

Figure 1 is a detailed perspective view of a device constructed according to the preferred embodiment of this invention;

Figure 2 is a detailed side elevation of the device;

Figure 3 is a detailed side elevation of the

device showing the method of operation of the bit on the mouth of a horse; and

Figure 4 is a detailed side elevation of a modification of the device.

Referring to the drawing wherein like numerals of reference designate corresponding parts throughout the several views, the numeral 10 designates a mouth bar of conventional construction which is adapted for use in the curbing of horses, the mouth bar 10 having an arched inner portion as at 11 which is adapted to press against the tongue of the horse. The mouth bar 10 is provided at the opposite end portions thereof with a pair of side bars 12 or the like which are of elongated construction and are preferably cast integrally with the mouth bar 10 although if desired the side bars 12 may be riveted or otherwise secured to the mouth bar 10. The side bars 12 are provided with a bridle loop 13 which is adapted to receive the conventional bridle. The ends of the side bars 12 are provided with looped portions or rings 14 for receiving driving reins 15 or the like.

The loops 13 are preferably in substantial alignment with the axes of the elongated bars 12 and the axes of the checking rings 14 are preferably spaced downwardly from the axes of the side bars 12. The bridle rings 13 are provided with downwardly extending or depending portions 16, and a ring member 17 is positioned upon the lower end portion of the extension 16, the ring 17 being adapted to receive a curb strap 18 or the like.

The extension 16 is preferably positioned in angular relation to the side bars 12 and the upper end portion of the extension 16 connects with the side bars 12 at a point spaced rearwardly from the mouth bar 10. The connecting point of the depending member 16 between the ring 13 and the side bars 12 is preferably arcuately inclined as at 19 and is adapted to receive between the inner edge portion of the ring 17 and the abutting edge of the side bar 12 the protruding portion of the mouth of the horse as at 20, it of course being understood that when the side bars 12 are moved rearwardly, the edges of the

horse's mouth will be forced outwardly a slight degree and the space between the ring members 17 and the side bars 12 is sufficient to receive the protruding edge of the horse's mouth so as not to pinch or otherwise chafe the mouth of the horse.

In the modification of this invention as disclosed in Figure 4, the side bars 12' are provided with lug members 21 adjacent the mouth bars 10 for loosely receiving ring members 22 so that an additional pair of reins or the like may be secured to the bit, the use of the reins attached to the rings 22 being particularly designed for ordinary driving where the horse is more or less gentle. As shown in Figure 4, the side bars 12 are provided with downwardly extending lug members 23 at the forward end thereof and ring members 24 are adapted to be loosely mounted in the lug members 23, the ring members 24 being adapted to receive reins 15' or the like.

In the use of this device, the mouth bar 10 is adapted to be placed in the mouth of the horse in the conventional manner, the side bars 12 being normally in substantial alignment with the mouth of the horse. The bridle is adapted to be secured to the ring members 13 in the conventional manner and the curb strap 18 positioned about the lower jaw of the horse's mouth so that the curb strap 18 and spaced rearwardly from the inner end of the horse's mouth so that the curb strap 18 will not chafe or pinch the mouth when under stress.

The curb chain carrier or curb strap carrier 17 protrudes down and back in such a way as to carry the curb strap or curb chain out from the corners of the mouth so as not to pinch the corners of the mouth, leaving room for the mouth corners to bulge back of the mouth bar when pull is applied to the reins, at the same time carrying the curb strap or curb chain in the chin groove of the horse. This curb strap or curb chain carrier 17 can be made into any type of curb bit made of any metal.

The bit with the curb strap or curb chain carrier is designed for riding horses where much turning, stopping, checking is done with the horse, as in polo, cow horse work, cavalry drills, etc. It is also of value in gaiting a horse where the horse is required to get into or against the bit, without pinching his mouth and also for the amateur whose hand is not certain, and especially for the young or tender mouthed horse who is always doing the unexpected, and just as firm for the tough mouthed horse which is sometimes caused by the mouth being pinched, causing lunging, rearing and head fighting.

When the horse becomes unruly or it is desired to suddenly check the horse, the reins 15 may be pulled rearwardly thereby swing-

ing the side bars 12, the mouth bar 10 serving as a pivotal member. The rearward movement of the ring member 14 will cooperatively force the curb strap 18 against the lower jaws of the horse and at the same time the arched portion 11 will bear against the tongue of the horse. When the side bars 12 are swung rearwardly, the mouth of the horse due to the upward movement of the curb strap 18 will be forced outwardly a slight degree and the protruding portion of the mouth will rest in the space between the curb ring 17 and the side bars 12, the space between these members being sufficient to adequately receive the protruding portion of the horse's mouth without in any way chafing or injuring the mouth.

The ring members 17, therefore, serve as a fulcrum or pivot, being held against movement by the curb strap 18, and the swinging of the side bars 12 will force the mouth bar or bit 11 downwardly and the horse will thus be placed under the complete control of the rider.

It will, of course, be understood that various changes and modifications may be made in the details of construction and design of the above specifically described embodiment of the invention without departing from the spirit thereof, such changes and modifications being restricted only by the scope of the following claim.

What is claimed is:—

In a bit including a pair of side bars, a mouth bar and means for receiving bridle and rein attaching members; an elongated extension secured to the upper end of each side bar and extending rearwardly and downwardly of the upper end of the side bar, said extension having an eye therein disposed rearwardly of the rear edge of the side bar, and a curb strap disposed in said curb strap away from said side bars whereby to prevent pinching of the mouth between the strap and the rear edge of the side bars.

In testimony whereof I hereunto affix my signature.

RALPH J. KERRUISH.
